UNITED STATES PATENT OFFICE.

JOHN H. GEORGE, OF BRIDGEPORT, CONNECTICUT, ASSIGNOR TO HAWTHORNE MANUFACTURING COMPANY, INC., OF BRIDGEPORT, CONNECTICUT, A CORPORATION OF CONNECTICUT.

ELECTRIC SWITCH.

1,411,620.

Specification of Letters Patent.

Patented Apr. 4, 1922.

Application filed December 6, 1917. Serial No. 205,728.

To all whom it may concern:

Be it known that I, JOHN H. GEORGE, a subject of the King of Great Britain, and a resident of Bridgeport, in the county of Fairfield and State of Connecticut, have invented an Improvement in Electric Switches, of which the following description, in connection with the accompanying drawings, is a specification, like characters on the drawings representing like parts.

This invention relates to electric switches, and is more particularly, though not exclusively, concerned with a switch adapted for the control of the lighting circuit or circuits of one or more lamps of a headlight or searchlight.

My invention will be best understood by reference to the following description, when taken in connection with the accompanying drawings of one specific embodiment thereof, while its scope will be more particularly pointed out in the appended claims.

In the drawings:

Fig. 1 is a central, longitudinal section, partly in elevation, of a searchlight equipped with a switch embodying my invention;

Fig. 2 is a front elevation of the switch;

Fig. 3 is a rear elevation of the same;

Fig. 4 is a partial front elevation, on an enlarged scale, of the switch with its front plate removed;

Fig. 4^a is a detail sectional view on line 4^a—4^a of Fig. 4;

Fig. 5 is a central, longitudinal section of the switch at the same scale as Fig. 4;

Fig. 6 is a sectional view, on line 6—6 of Fig. 5, looking toward the left;

Fig. 7 is a sectional view, on line 7—7 of Fig. 5, looking toward the right;

Fig. 8 is a detail, sectional view on line 8—8 of Fig. 7; and

Figs. 9, 10 and 11, are diagrammatic views showing the lighting circuit in three positions of the switch, the first showing the switch positioned for the lighting of one lamp, the second with the switch in its "off" position, and the third showing the switch positioned for the lighting of the second lamp.

Referring to the drawings, and to the embodiment of my invention which is illustrated therein, I have shown a head-light or search-light equipped with an incandes-

cent electric bulb 15, having a base 16 which may be, and herein is, of the commercially known "Ediswan" type, provided with a pair of laterally projecting pins 17, engaging bayonet slots 18 in a socket 19. These bulbs are of two types, one having a single, centrally-located terminal, and a circumferential terminal, while the other is provided at its rear or inner end with a pair of terminals. The latter type is herein selected for illustration, and has two terminals 20 and 21. Cooperating with these terminals are contacts 22 and 23, carried by a plug 24 mounted in the socket 19, and encircled by a spring 25, which urges the contacts 22 and 23 against the terminals 20 and 21, respectively.

The lamp is also provided with a second incandescent electric bulb 26, which may be and is herein of greater candle power than the bulb 15, the bulb 26 being provided with a base 27 having a pair of laterally projecting pins 28 located in bayonet slots 29 in a socket 30. This bulb also is provided with terminals 31 and 32, cooperating with spring-pressed contacts 33 and 34, respectively, best shown in Fig. 5. The switch proper comprises two co-axially disposed, relatively rotatable, units 35 and 36 (see Figs. 5 and 8). The unit 35, which may be, and herein is, non-rotatable, is provided with an interior chamber 37, best shown in Figs. 5, 6 and 7, in which the rotatable unit 36 is located. The addition of the unit 36 makes the chamber 37 entirely closed. The chamber, therefore, forms an air-tight, dust-proof housing for the contacts, which will be presently described.

The non-rotatable unit 35 herein comprises two end members 38 and 39, and an intermediate member 40, all preferably formed of some suitable insulating substance, such for example as compressed fibre, which is well adapted to the purpose, since it may be pressed into the desired form by means of molds or dies. Likewise, the rotatable unit 36 comprises a member 41 formed of suitable insulating material, also preferably consisting of compressed fibre. Since these parts are formed of insulating material, they form suitable mountings, in which the contacts and conductors herein-after described can be directly mounted,

without the need of further insulation. Preferably, the members 38, 39 and 40, are suitably interlocked and rendered self-centering when assembling them, the intermediate member 40 for this purpose being provided with an annular flange 42 projecting into and snugly fitting an annular recess 43 in the member 39, and provided also with a cylindrical centrally located boss 44, 10 projecting into and snugly fitting a cylindrical recess 45 in the member 38. As a means for fastening together the members 38, 39 and 40, I have herein provided a pair of fastening members preferably consisting 15 of bolts 46, best shown in Figs. 2, 3, 6 and 7, having nuts 47 to clamp the three members together.

Any suitable means may be provided properly to position the members 38 and 40 20 with reference to each other, but in the present example, I have provided the member 40 with a pair of lugs 48, best shown in Figs. 4 and 6, projecting into and snugly fitting depressions 49 in the member 38. As a 25 means to position the members 40 and 41 with reference to each other, and to limit the turning movement of the member 41, I have herein provided the latter with a lug 50, best shown in Figs. 7 and 8, projecting 30 into a segmental recess 51, best shown in Fig. 6. As an aid in the proper positioning of the member 39 with reference to the member 41, the latter is preferably provided with one or more, herein three shallow 35 depressions 52, best shown in Figs. 7 and 8, to receive a yielding positioning pin 53, having a rounded or beveled end to enter the individual depressions. This pin is mounted to slide axially in a deep depression 54 in 40 the member 39, and a spring 55 beneath or back of the head of this pin urges the latter toward the member 41.

It should now be evident that the switch parts thus far described can be easily and 45 quickly assembled, without the possibility of error, by first introducing the member 41 into the member 39, and making sure that the pin 53 is in the middle depression 52, and then introducing the lug 50 into the 50 middle of the segmental recess 51. The lugs 48 on the member 40, entering into the depressions 49 in the member 38, position the members 38 and 40 with reference to each other. The holes for the bolts 46 will now 55 be properly aligned, so that when the bolts are introduced, the several parts will be correctly positioned with relation to one another to perform their proper functions with reference to the contacts now to be described.

60 The contact pins 33 and 34 are mounted in a well-known manner to slide axially in tubular guides 56 and 57, best shown in Fig. 5, mounted in fixed position in the member 40, and containing springs 58 and 59, which 65 serve to urge the contacts 33 and 34 in an

outward direction. Shoulders 61 and 62 on the contacts 33 and 34, respectively, limit the outward movement of the latter under the influence of their respective springs. The inner ends of the tubular guides 56 and 70 57 are provided with heads 63 and 64, constituting fixed contacts whose end faces are exposed within the chamber 37, as best shown in Fig. 6. These contacts are in constant electrical connection with the terminals 31 75 and 32, respectively, of the bulb 26, so that when said contacts are connected in circuit with a suitable source of current, said bulb is lighted.

Leading from the contacts 22 and 23, respectively, of the plug 24 (see Fig. 1) are two insulated conducting wires 65 and 66, which extend into recesses 67 and 68, respectively, in one face of the member 40 (see Figs. 4, 5 and 6). The ends of these 80 wires are bared, doubled back upon themselves and interlocked with suitable terminals 69 and 70, also mounted within and protected by the grooves 67 and 68. These terminals may be secured in place by any 85 suitable means, as, for example, rivets 71 and 72 which extend through the member 40 to the chamber 37, where they are provided with heads 73 and 74, constituting contacts which are preferably embedded flush with 90 the front face of said chamber.

Two other flexible insulated conducting wires 75 and 76 which may be connected to any suitable source of current not shown, are also connected to the non-rotatable part 100 of the switch. The wire 75 preferably extends into the groove 67, which is prolonged for such purpose, and the end of said wire is bared, doubled upon itself, and interlocked with the terminal 69 within said 105 groove. The wire 76, however, extends into still another groove 77, where its end is bared, doubled back upon itself and interlocked with a terminal 78. The latter is then secured in place by a rivet 79 extending 110 through the member 40 to the interior of the chamber 37, where it is provided with a head 80 constituting a contact preferably flush with the front face of said chamber. Thus it is apparent that all the flexible conducting 115 wires are secured to the non-rotatable unit of the switch, and moreover that their mode of attachment is such that their ends are well protected against the possibility of injury, and are so housed that the possibility of 120 short circuits is eliminated.

While I have herein shown the switch adapted for the control of the lighting circuits of two lamps or bulbs, it should be understood that it is equally well adapted to 125 the control of only a single lamp or bulb. It should also be understood that, by a slight modification, it is equally well adapted for the use of a so-called single-pole bulb. Where there are two bulbs, as in the present 130

example, it is desirable that when one is in circuit, the other shall be out of circuit. To this end, I have herein provided the rotatable unit 36 with three contact plates 81, 82 and 83. By reference to Figs. 9, 10 and 11, it will be observed that the plate 81, when swung from the position shown in Fig. 10 to the position shown in Fig. 9, makes contact with the contact members 31 and 73. Likewise, when the switch is in this position, the contact plate 82 makes contact with the contact members 80 and 32. Hence, at this time, a circuit is completed to the bulb 26. When, on the other hand, the unit 36 is turned from the position shown in Fig. 9 to the position shown in Fig. 10, the contact plates 81 and 82 are carried out of contact with their respectively pairs of contacts 73, 31, and 80, 32, so that the lamp circuit is broken.

When, now, the unit 36 is turned from the position shown in Fig. 10 to that shown in Fig. 11, the contact plate 82 contacts with the contact member 74, while the plate 83 contacts with the contact member 80. By simply providing a permanent connection between the plates 82 and 83, a circuit to the bulb 15 will be completed when the switch is placed in the position shown in Fig. 11.

This permanent connection may take other forms, but in the present example, I have shown them connected by an integral conductor 84. In fact, the two plates are preferably stamped as a single piece. When, on the other hand, the switch is restored to the position shown in Fig. 10, the plates 82 and 83 are moved out of contact with the contact members 74 and 80, respectively, and the circuit to the bulb 15 is broken.

The plates 81, 82 and 83 may be otherwise suitably constructed and mounted on the insulating member 41, but in the present example, each of said plates is provided at its terminal portion or portions, as the case may be, with slightly elevated rounded projections, as clearly shown in Figs. 5 and 7, and said plates are mounted on spring-pressed plungers 85, 86 and 87, which urge the plates in an axial direction against the front face of the chamber 37, thereby to ensure proper working contact of said plates with the fixed contact members which are mounted in the insulating member 40. Preferably, the plates 81, 82 and 83 are sunk flush into the front face of the insulating member 41, the latter for this purpose being provided with an irregularly shaped depression 88, best shown in Figs. 7 and 8, which depression for the most part is shaped to correspond with the outlines of said plates, and thus serves to hold them accurately in their proper positions with reference to the insulating member 41.

It should now be apparent that since all of the conducting parts are fully enclosed and insulated from one another, there is no possibility of the occurrence of short circuits, or any injury whatever to the working parts. It is also evident that the switch can be assembled and dismounted by a comparatively unskilled person, because it is practically impossible to make any mistake. In the operation of the switch, no error can occur, because it has three definite positions determined by the three depressions 52, 75 which receive the positioning pin 53 (see Figs. 7 and 8), the middle depression corresponding to the off position of the switch, and the other two depressions corresponding, respectively, to the two positions in 80 which the switch completes the circuits to the two bulbs. Obviously, in the case of a lamp having a single bulb only, one of these depressions may be omitted if desired, although its omission is unnecessary, as it is 85 evident that the switch without change can be used for either one or two-lamp circuits.

The socket may be otherwise appropriately secured in place in the insulating member 38, but in the present example, said 90 socket is provided with a plurality of lugs 89 in the form of tongues stamped out of and struck up from the rear end of the socket and embedded in the material of which the member 38 is molded. This can 95 be conveniently accomplished by setting the socket member in the die or mold, and then flowing or forcing the insulating material thereinto about the socket, whereby the latter becomes interlocked with and permanently held in its place in the insulating member, as clearly indicated in Fig. 5.

The switch may be used in connection with lamps of other types, but in the present example, I have shown the same mounted in 100 a headlight or searchlight having a casing 90, within which is a reflector 91 associated with the bulb 26 in coaxial relationship therewith, while the switch occupies a chamber formed between the casing and the reflector, as shown in Fig. 1.

Although my invention relates to the switch per se, for the sake of illustrating one of its many applications, I have herein shown the same in connection with the operating means, which forms the subject matter of another application. In the example shown, the rear end of the unit 36 is provided with a rearwardly extending boss or hub 92, in the form of a prism having any 110 suitable number of faces, and this boss has a snug fit in a correspondingly shaped aperture 93 of a collar 94, the latter being secured in any suitable manner to the casing 90, as by electrically welding the same. The 115 unit 36 is provided with an actuating member in the form of a rod 95, which in the present example has at its forward end an enlarged head 96 embedded in and interlocked with the member 41, which is molded 120

125

130

or pressed in a mold or die, thus effecting a permanent union between the rod 95 and the insulating member 41. The rod 95 extends rearwardly through a handle 97 of 5 the casing, and is provided exteriorly of the latter with a knob 98, by means of which the rod may be turned to operate the switch. This knob is herein secured to the rod 95 by providing the latter with a prismatic portion 99 embedded in a correspondingly shaped hole 100 in the knob, while a screw 101, threaded into the end of the rod secures the knob to the rod.

While I have herein shown and described one form or embodiment of my invention for illustrative purposes, and have disclosed and discussed in detail the construction and arrangement incidental to one specific application thereof, it is to be understood that the invention is limited neither to the mere details or relative arrangement of parts, nor to its specific embodiment herein shown, but that extensive deviations from the illustrated form or embodiment of the invention may be made, without departing from the principles thereof.

Having thus described my invention, what I claim and desire by Letters Patent to secure is:

30 1. In an electric switch and socket structure, the combination of two relatively rotatable inner and outer units forming together an interior, closed chamber, a set of contacts carried by said units within said chamber, a set of conductors carried by and extending laterally into said outer unit and connected to said contacts, a contact actuator extending from one end of said outer unit, and a socket associated with said contacts and carried by 40 the other end of said outer unit.

2. In an electric switch, the combination of two relatively rotatable units forming together an interior, closed chamber, a set of contacts carried by said units within said chamber, and endwise engaging means within said chamber to limit the extent of relative rotation of said units.

3. In an electric switch, the combination of two relatively rotatable units, one comprising an insulating housing including two end members and an intermediate member interposed therebetween and abutting end to end, said intermediate member and one of said end members independently of the other end member forming together an inner chamber, within which the other of said units is mounted, and a set of cooperating contacts carried by said units within said chamber.

4. In an electric switch, the combination of two relatively rotatable units, one of said units comprising a plurality of insulating members abutting end to end and forming together an interior chamber, means to secure said members together end to end, the 65 other of said units comprising an insulating

member located in said chamber, and cooperating contacts carried by said members within said chamber.

5. In an electric switch, the combination of two relatively rotatable units, one of said units comprising two end members and an intermediate member abutting end to end and having interengaging projections, said intermediate member and one of said end members forming together an interior chamber, having a circumferential wall formed by such members, a plurality of contacts mounted in said intermediate member and extending to said chamber, and the other of said units comprising an insulating member located within said chamber and a contact carried thereby and cooperating with the first-mentioned contact member.

6. In an electric switch, the combination of two relatively rotatable units, one of said units comprising two end members and an intermediate member abutting end to end said intermediate member and one of said end members forming together an interior chamber, and said intermediate member and the other end member together forming other chambers, conductors leading into said other chambers, contacts connected to said conductors and extending through said intermediate member to said interior chamber, other contacts extending through said intermediate member to said interior chamber, and the other of said units comprising an insulating member located within said inner chamber, and contacts carried by the last mentioned insulating member and cooperating with the first mentioned contacts.

7. In an electric switch, the combination of two relatively rotatable units, one of said units comprising two end members and an intermediate member abutting end to end, said intermediate member and one of said end members interengaging with each other and forming together an interior chamber, and said intermediate member and the other end member interengaging with each other and forming together other chambers, conductors leading into said other chambers, contacts connected to said conductors and extending through said intermediate member to said interior chamber, other contacts extending through said intermediate member to said interior chamber, and the other of said units comprising an insulating member located within said inner chamber, and contacts carried by the last-mentioned insulating member and cooperating with the first-mentioned contacts.

8. In an electric switch, the combination of two relatively rotatable units having cooperating contacts and assembled by relative axial movement, and means to enforce the assembling of said units in predetermined relationship when brought together endwise.

9. In an electric switch, the combination of two insulating members arranged face to face and mounted to turn one with relation to the other, and cooperating contacts carried by said members, respectively, said contacts including a set of three and a pair carried by one of said members, and three contacts carried by the other member and arranged in one position to bridge two contacts of said set of three and in another position to bridge and make connection between two contacts of said set and the two contacts of said pair, respectively.
- 5 In testimony whereof, I have signed my name to this specification.

JOHN H. GEORGE.
